UNITED STATES PATENT OFFICE.

AUGUST JEUDE, OF OKRIFTEL, GERMANY, ASSIGNOR TO AARON VAIL ROWLEY, OF FRANKFORT-ON-THE-MAIN, GERMANY.

BUTTONHOLE-CUTTER.

SPECIFICATION forming part of Letters Patent No. 715,810, dated December 16, 1902.

Original application filed August 7, 1901, Serial No. 71,181. Divided and this application filed May 16, 1902. Serial No. 107,610. (No model.)

To all whom it may concern:

Be it known that I, AUGUST JEUDE, mechanician, residing at Okriftel, near Hattersheim-on-the-Main, in the German Empire, have invented new and useful Improvements 5 in Buttonhole-Cutters, of which the following is a specification.

My invention relates to an improvement in the form of the knife which cuts the button-hole preliminary to sewing. These knives in buttonhole-cutters have usually an eye at one end to cut out a little piece of fabric to form the so-called "eye" of the buttonhole. The improvement relates to a special needle or 10 hook arranged inside the eye of the knife and serving to remove securely the cut-out pieces 15 of fabric.

The present application is a division of another application for patent filed by me in the 20 United States Patent Office on August 7, 1901, Serial No. 71,181, which application relates to improvements in buttonhole - sewing machines, while the present case, as above mentioned, relates to a device for forming button-holes and removing the pieces of fabric which 25 are cut out in the formation of the button-hole.

The invention will be fully described hereinafter and the features of novelty pointed 30 out in the appended claims.

In the accompanying drawings, Figure 1 is an elevation of one form of my improved buttonhole-cutter with parts in section. Fig. 2 is an end view with parts in section on line 35 2 2 of Fig. 1, and Fig. 3 is a bottom plan view.

a is the knife for cutting the buttonhole, and *b* is its eye.

c is the needle, the end of which protrudes under the edge of the eye *b* and is provided 40 with a hook *d*. The needle is tapering and attached at its broader upper end by an arm to the body of the knife *a*. At the point *e*

there is a curved edge, preferably overhanging the eye *b*.

The action of the device is as follows: The 45 hook *d* will stitch into the fabric and raise the piece of fabric cut out by the eye *b*. These pieces will assemble on the needle and move up to the edge *e*. This will cut one side of every piece of fabric through, so that it falls 50 off the needle.

It will be understood that the needle *b* has a sharp lower edge at the bend *e*, as shown in Fig. 2, and that the pieces of fabric when cut or slit by the said edge fall on the side away 55 from the knife *a*.

Now what I claim, and desire to secure by Letters Patent, is the following:

1. In a buttonhole-cutter the combination with an eyed knife of a hooked needle provided inside the eye of the knife.

2. In a buttonhole-cutter the combination with an eyed knife of a needle provided inside the eye of the knife and provided with a hook protruding downward under the edge 65 of the knife.

3. In a buttonhole-cutter the combination with an eyed knife of a needle provided inside the eye of the knife and tapering downward.

4. In a buttonhole-cutter the combination with an eyed knife of a needle provided inside the eye of the knife and with an arm carrying the needle at its upper end and having a cutting-shoulder at its bottom side, substantially as described.

In testimony whereof I have signed my name to this specification in the presence of two subscribing witnesses.

AUGUST JEUDE.
